UNITED STATES PATENT OFFICE.

SAMANTHA I. LOGAN, OF LOUISVILLE, KENTUCKY.

DESIGN FOR A SPOON.

SPECIFICATION forming part of Design No. 21,304, dated January 19, 1892.

Application filed December 14, 1891. Serial No. 415,086. Term of patent 7 years.

To all whom it may concern:

Be it known that I, SAMANTHA I. LOGAN, a citizen of the United States, residing at Louisville, in the county of Jefferson and State of Kentucky, have invented and produced a new and original Design for a Spoon, of which the following is a specification, reference being had to the accompanying drawing, forming a part thereof.

10 The spoon as designed by me is intended as a "Scotch-Irish" souvenir spoon, the leading feature being a bowl representing a thistle and a handle representing the stem and leaf of a thistle and the leaf displaying the leaves and blossom of a shamrock.

15 Referring to the drawing, in which the spoon is shown in elevation, A represents the spoon; B, the bowl; C, the stem portion, and D the handle. The bowl is made in the form of a thistle and is drawn to a point below to form the end of the bowl, the surface being etched, engraved, enameled, or otherwise or-

namented to represent a thistle. The handle proper D is made to conform to the shape of a thistle-leaf, the edges being pointed and the 25 surface being formed with veins, as shown. On the surface is also displayed a spray of shamrock E, the stem of which terminates at the point of junction of the handle proper with the stem of the spoon. The stem C is 30 formed to represent the stem of the thistle, the edges being provided with points, as shown.

I claim—

The design for a spoon, as herein shown 35 and described, consisting of a bowl in the semblance of a thistle and a handle representing a thistle stem and leaf, on the face of which a spray of shamrock is displayed.

SAMANTHA I. LOGAN.
